UNITED STATES PATENT OFFICE.

JOHN V. DUNN, OF NEW LEXINGTON, OHIO.

PRICE-TAG HOLDER.

Application filed December 3, 1923. Serial No. 678,264.

To all whom it may concern:

Be it known that I, JOHN V. DUNN, a citizen of the United States, residing at New Lexington, in the county of Perry and State 5 of Ohio, have invented new and useful Improvements in Price-Tag Holders, of which the following is a specification.

This invention relates to a price tag holder, the general object of the invention being 10 to provide means for holding a price tag on a shoe so that it is not likely to be knocked off in handling the shoe.

Another object of the invention is to provide means on the holder for engaging the 15 eyelets or hooks of a shoe so that the edges of the opening in a shoe are held together.

This invention also consists in certain 20 other features of construction and in the combination and arrangement of the several parts, to be hereinafter fully described, illustrated in the accompanying drawings and specifically pointed out in the appended claim.

In describing my invention in detail, reference will be had to the accompanying 25 drawings wherein like characters denote like or corresponding parts throughout the several views, and in which:—

Figure 1 is a view of a shoe showing the 30 invention in use.

Figure 2 is a section on line 2—2 of Figure 1.

Figure 3 is a view of the holder itself.

As shown in these views, the holder is formed of one piece of wire which is shown 35 at 1, and it is bent upon itself to form the coils 2 for gripping the price tag, shown at A, between them. After forming the coil the wire is twisted to form a stem 3 and each part of the wire is bent at right angles 40 and then bent upwardly and downwardly to form a U-shaped loop 4. These loops are adapted to engage the eyelets of a shoe, shown at B, so that the edges of the opening in the shoe are held together by the device while the device is in a position to hold 45 the price tag. Thus the device will not only act as a price tag holder but it will also act to hold the shoe in better shape.

It is thought from the foregoing description 50 that the advantages and novel features of my invention will be readily apparent.

I desire it to be understood that I may make changes in the construction and in the combination and arrangement of the several 55 parts, provided that such changes fall within the scope of the appended claim.

What I claim is:—

A device of the class described comprising 60 a member having coils at its center for holding a price tag and U-shaped portions at its ends for engaging the eyelets of a shoe.

In testimony whereof I affix my signature.
JOHN V. DUNN.
